UNITED STATES PATENT OFFICE.

CHRISTIAN W. MEINECKE, OF JERSEY CITY, NEW JERSEY, ASSIGNOR TO WHITALL TATUM COMPANY, OF NEW YORK, N. Y., A CORPORATION OF NEW JERSEY.

ATOMIZER AND NEBULIZER.

No. 918,762.

Specification of Letters Patent. Patented April 20, 1909.

Application filed June 19, 1908. Serial No. 439,291.

To all whom it may concern:

Be it known that I, CHRISTIAN WILLIAM MEINECKE, residing in Jersey City, county of Hudson, and State of New Jersey, have 5 invented a certain new and useful Improvement in Atomizers and Nebulizers, of which the following is a full, clear, and exact description.

My invention relates to that class of the 10 above devices which is used for introducing medicated sprays and vapors into the nostrils as in the treatment of catarrh and kindred troubles and, more particularly, to that species of the class in which the functioning nozzle is surrounded by a cap or 15 sleeve, generally coned, for the purpose of closing the nostril so as to prevent leakage.

In atomizers of the above mentioned 20 character no adequate provision has hitherto been made, so far as I am aware, for the condensed fluids resulting from their use and these fluids either drain back upon the cap and atomizer bottle, or, if they fall within the cap, pass back into the original medicated supply. As this drainage necessarily 25 carries mucous and other nasal secretions with it, some or all of which are the result of diseased conditions, and as, indeed, such secretions are generally stimulated to excess 30 by the very application of the treatment, it follows that the supply of medicament quickly becomes contaminated and a breeder of disease rather than a hindrance thereto; certainly to expect improvement 35 in diseased tissue by applications of a solution of its own detritus is neither reasonable nor in accord with the teachings of medical science. It is a matter of common 40 knowledge, also, that nasal atomizers are frequently used in common by various members of one family; in such cases a diseased condition existing in one individual may quickly be transmitted to others who would otherwise, perhaps, have remained free 45 from it.

It is the object of my invention to remedy 50 the faulty conditions above set forth and to provide a means by which the infected drainage is kept apart from the pure original solution and the atomizer as a whole maintained in a sanitary state. This object I 55 attain by a special construction, better understood by reference to the accompanying drawings, through which all drainage passes into a separate receptacle, apart from

that containing the original medicated solution, where it remains without any opportunity for spreading infection and from which it may be removed at convenient times.

My invention may be embodied in a considerable number of different modifications 60 without departing from its essence and in the drawings herewith I show several of my preferred embodiments.

Figure 1 is an elevation, part section, of 65 an atomizer in which the drainage receptacle is entirely outside of the solution container. Fig. 2 is an elevation, part section, of an atomizer in which the drainage receptacle is entirely inside of the solution 70 container. Fig. 3 is an elevation, part section, of an atomizer in which the drainage receptacle is outside of and surrounds the solution container, and Fig. 4 is an elevation, part section, of a form in which the 75 drainage receptacle is a detachable cup held by and above the atomizer cap.

In all the figures, A is the solution container, and B, the conical cap surrounding the nozzle, C, which latter is a part of and 80 is supported by the screw cap, H, which constitutes the main cap of the atomizer.

In Fig. 1 the drainage receptacle, D, is a screw necked bottle fitting into a cap, E, sustained at the end of a bent tube, F, the 85 bore of which joins the bottle and the floor, G', of the nozzle cap, G. This bottle, into which passes the drainage from G, is readily removed for cleaning.

In Fig. 2 the drainage receptacle, D, is 90 inside the solution container, A, and is a screw necked bottle, the cap of which, E, is soldered or otherwise fastened to the roof, H¹, of the large screw cap, H; a tube, I, pierced through H¹ and G', just over D, carries off the drainage, and to insure this taking place rapidly a second tube J, ending well 95 above the level G' and opening into D below equalizes the air pressure. In this form the drainage receptacle is protected from breakage by the larger and stouter solution container, A, which latter must first be removed before access is had for the removal of D.

In Fig. 3 the construction is almost identical with that of Fig. 2 except that the outer 105 bottle now constitutes the drainage receptacle and the inner bottle the solution container. Drainage is, as in Fig. 2, brought from the cap G by holes I¹ and J¹ in the nozzle cap floor and screw cap roof but the hole 110

J¹ must now lie between the outer circumference of contact of the container, A, and the inner circumference of the drainage receptacle D. In practice I prefer to use a number of holes, I¹ and J¹, circularly disposed instead of merely one hole as in Fig. 2.

In Fig. 4 the drainage receptacle takes the form of a cylindrical cup, K, having a flared rim, L, at the top and a reentrant flattened sleeve, M, of a height approximately equal to that of the cup; it is adapted to slip easily within the nozzle cap, G, with the sleeve, M, closely embracing the nozzle pipes, N, and the conical cap, B, is now adapted to slip into it and to be removable therefrom just as, in Figs. 1, 2, and 3, it was similarly fitted to the nozzle cap G. To clean the atomizer the cup, K, is withdrawn by its rim and emptied, after first removing the conical cap, B, after which both it and cap B may be replaced.

Having now described my invention I claim:

1. In a nasal atomizer having a substantially closed receptacle for holding the fluid to be atomized, an independent detachable drip receptacle adapted to receive the condensed spray and discharges which may return from the nasal passages treated.
2. In a nasal atomizer having a substantially closed receptacle for holding the fluid to be atomized, an independent detachable drip receptacle adapted to receive the condensed spray and discharges which may return from the nasal passages treated, said drip receptacle being located entirely outside of the fluid holding receptacle.
3. In a nasal atomizer having a substantially closed and detachable receptacle for holding the fluid to be atomized, an independent drip receptacle adapted to receive the condensed spray and discharges which

may return from the nasal passages treated, said drip receptacle being located entirely outside of the fluid holding receptacle.

4. In a nasal atomizer having a nozzle adapted to engage the nostril, a substantially closed but openable drainage receptacle having connection with said nozzle and adapted to receive condensation, and also to receive drainage from the parts treated.

5. In a nasal atomizer having a nozzle adapted to engage the nostril, separate substantially closed but openable receptacles:— the one adapted to contain the atomizing medium; and the other having connection with the nozzle so as to receive therefrom the condensation, and also to receive drainage from the parts treated.

6. In combination with a nasal atomizer having a cap structure carrying atomizing tubes, substantially closed receptacles independently openable therefrom and adapted to contain: the one the fluid to be atomized; and the other the condensation, and also to receive drainage from the parts treated.

7. In combination with a nasal atomizer having a main cap structure carrying atomizing tubes, a substantially closed receptacle openable therefrom and adapted to contain the fluid to be atomized; a second substantially closed receptacle openable from a second cap structure; and a connection between the main cap and this latter receptacle whereby drainage from affected parts is kept separate from the source of supply.

In testimony whereof I have hereunto set my hand in the presence of two subscribing witnesses.

CHRISTIAN W. MEINECKE.
